Inventor
Charles F. Brigham.

CHARLES F. BRIGHAM, OF WORCESTER, MASSACHUSETTS.

Letters Patent No. 85,204, dated December 22, 1868.

RUNNER-ATTACHMENT FOR CARRIAGES.

The Schedule referred to in these Letters Patent and making part of the same.

Know all men by these presents:

That I, CHARLES F. BRIGHAM, of the city and county of Worcester, and Commonwealth of Massachusetts, have invented certain new and useful Improvements in Runner-Attachments for Carriages or Wheeled Vehicles; and I do hereby declare that the following is a full, clear, and exact description of the same, reference being had to the accompanying drawings, forming a part of this specification, in which—

Figure 1 represents a perspective view of my improved runner-attachment;

Figure 2 represents a rear view of the same;

Figure 3 represents a plan view of the box for holding the axles;

Figure 4 represents a longitudinal section of the axle and box, on line A B, fig. 3;

Figure 5 represents a transverse section of the same, on line C D, fig. 3; and

Figure 6 represents a side view of my improved runner-attachment, when constructed in a somewhat different manner to be applied to double carriages.

To enable those skilled in the art to which my invention belongs, to make and use the same, I will proceed to describe it more in detail.

The nature of my invention consists—

First, in the combination, with the front and rear axles in carriages, or other wheeled vehicles, of long runners, in the manner hereafter explained.

Second, in the peculiar construction and arrangement of the boxes or sockets for holding the axles, as hereafter explained.

Third, in the peculiar construction, combination, and arrangement of the runners, fenders, and boxes, as hereafter described.

In the drawings, the part marked A is the body of the carriage, mounted in the usual manner upon the axles B, to the journals of which, after removing the wheels, runners C are attached, to admit of the carriage being used as a sleigh.

The runners C are long enough to extend the length of the carriage, and have fastened to the top ends of the studs F, by which they are supported, raves D and fenders E, both of which extend the length of the carriage, and have securely fastened between them, near their front and rear ends, square or other properly-shaped pieces of wood or metal, G, to which are bolted or screwed journal-boxes H, to receive the wheel-journals at the ends of the axles B.

The journal-boxes which are to receive the ends of the rear axle, are secured to the upper side of the fenders E and pieces G, and the boxes which are to receive the ends of the forward axle are secured to the lower side of the fender E and pieces G. In this manner the difference of height between the front and rear axles is retained, and the body of the carriage held in the same position as when mounted on wheels.

The journal-boxes H are made to fit the wheel-journals a, to which they are secured, in the same manner as the wheels, by the nuts c.

Slots are formed in the plates b of the journal-boxes H, through which pass the bolts or screws I, which hold them to the pieces G, and by means of which the boxes H can be adjusted back and forward.

The distance across the pieces G, from the inside of the raves D to the outside of the fender E, is a little more than the length of the wheel-journals a, thereby forming a guard for the purpose of preventing injury to the ends of the axles B, by coming in contact with posts or passing vehicles, and also to prevent the entangling of skirts or robes with the ends of the axles B.

The studs F and fenders E are suitably braced to insure strength, as fully indicated in the drawings.

When applying my invention to double carriages with hanging steps f, the fenders E and raves D may be made in sections, as indicated in fig. 6, leaving spaces to accommodate the steps f.

The journal-boxes H may be made of any convenient height and pattern, to conform to the style of the carriage upon which they are used.

It will be seen, from the foregoing description, that by my invention the body of any wheeled vehicle can be combined with runners, to be used as a sleigh, at a trifling expense, as compared with the outlay necessary to purchase sleighs of equal style of finish, while at the same time the carriage-springs add very much to the ease of movement.

Then, again, it requires but little space or room for storing the runners when not in use, as compared to the room required for storing ordinary single or double sleighs.

My invention has been practically tested, and is highly prized, especially by persons residing in localities where the fall of snow is such that the sleighing lasts but a few days or weeks at a time.

In case it is necessary to elevate or depress the axles, blocks may be placed between the boxes H and the pieces G, as the case may be.

Having described my improved runner-attachment for carriages,

What I claim therein as new and of my invention, and desire to secure by Letters Patent, is—

1. The combination, with the long runners C, raves D, and fenders E, of the boxes H, arranged, in relation to each other, substantially as shown in the drawings, for supporting the carriage-body in an even and proper manner, as described.

2. The combination, with the raves D, fenders E, and carriage-body A, of the adjustable axle-boxes H, substantially as and for the purposes set forth.

Witnesses: CHARLES F. BRIGHAM.
THOS. H. DODGE,
D. L. MILLER.
